[57] CLAIM

The ornamental design for a radio, as shown and described.

DESCRIPTION

FIG. 1 is a front and left side perspective view of a radio showing my new design;

FIG. 2 is a rear and right side perspective view thereof;

FIG. 3 is a front elevation view thereof;

FIG. 4 is a top plan view thereof;

FIG. 5 is a rear elevation view thereof; and

FIG. 6 is a left side elevational view thereof.

The headset shown in FIG. 1 was omitted from FIG. 2 through 6 for ease of illustration.

FIG. 1.

FIG. 2.

FIG.3.

FIG.4.

FIG.5.

FIG.6.
